RAIL SHIFT MECHANISM FOR LINE CAST-
ING AND COMPOSING MACHINESLester M. Walden, Chicago, Ill., assignor to Tele-
type Corporation, Chicago, Ill., a corporation
of Delaware

Application October 27, 1933, Serial No. 695,404

11 Claims. (Cl. 199—29)

The present improvement relates to linecasting and composing machines and more particularly to an automatic mechanism for operating such machines under the control of stored signals.

In its preferred embodiment, as herein disclosed, the improvement is adapted particularly to a control unit mechanism such as is completely described and illustrated in copending application Ser. No. 584,387, filed January 2, 1932, to which reference should be had for a full and comprehensive disclosure of the general construction of control units of this class.

In the control of linecasting and composing machines, which consists of selectively releasing the matrices or matrix elements, a comparatively high rate of operating speed may be attained within which the principal composing mechanism is capable of responding faithfully so that, as the several matrices of a line of composition are selectively released, they will gravitate in their selected order and be received in the assembling block in the same order. This gravitational assembling of the matrix elements is characteristic of all commercial line composing machines, and while the distribution of matrix magazine channels may be so arranged as to permit slower falling, matrices shorter distances in which to travel from their point of release to that of the assembly as compared with the distances to be travelled by faster falling matrices so as to equalize the traveling time for all matrices, yet the time thus consumed by each matrix in gravitating to the assembling level is considerably in excess of the time required for performing the automatic selective release thereof.

As a result of these characteristics, consecutive matrix release signals and the functions resulting therefrom may be executed automatically at comparatively high operating speeds, because, as explained, the several classes of matrices may be suitably arranged in their channels so that each matrix may consume the same or nearly the same amount of time in arriving at a common destination, the point of assembly. In the case of certain other functions, however, the performance of which must await the full and complete reception into the assembling block of the preceding matrices, a proportional prolongation of the interim between the sensing of the function selecting signal and the completion of its performance as compared with the interim between the sensing of a matrix selecting signal and its functional response, must be introduced.

One such special function is the rail shift op-

eration in the assembling block, which is described in the copending application referred to above. The rail located in the assembling block, which may by its presentation or withdrawal from the ingress passage thereof, determine one of two receivable conditions for subsequently selected matrices, may be of any of several well-known general constructions. In the following description, a longitudinally shiftable rail has been selected to exemplify the present invention.

While this retarded operation mechanism is being illustrated and described in connection with the rail shifting operation, this is by way of example only; the principles underlying the present invention having equally important and practical application to other collateral functions in association with similar or kindred mechanisms.

Accordingly the present invention has for its object the provision of a retarded action mechanism that may be applied to a control mechanism, driven by a more rapidly operating mover and initiated into alternative conditions of operation by each of a pair of selectable elements.

The application of the present invention contemplates the provision of an operating shaft that may be continuously moving and whose speed of performance is more nearly related to the higher speed which may prevail during the execution of the major functions of the composing mechanism. This shaft is provided with a helical section or spiral, a portion of which is inclined in one direction and an opposite and symmetrical portion of which is inclined in the other direction. The threaded section is straddled by a yoke or saddle member having oppositely and inwardly pressed lugs that are adapted to engage the corresponding threaded sections described, each to each. The saddle member is capable of slight transverse motion with respect to the shaft, so that either of its lugs may be made to engage the threads of its associated helical section, so that with the shaft rotating constantly in one direction, longitudinal motion is imparted to the saddle in a derivative direction corresponding to the particular lug and thread engagement. The saddle member is supported for limited longitudinal movement and by suitable mechanical linkage is connected to the operating arm of the shiftable rail referred to above, so that its longitudinal movement with respect to the driving shaft is imparted to the shiftable rail.

The transverse motion whereby the saddle member is made to engage with one or the other of its lugs its associated threaded section of the driving shaft is received through the reciproca-

tion of its supporting bracket, which is moved by a lever having pivotal connection with each of two selectable bars. The bars are of the class described in the copending application referred to above and are adapted to be individually selected in response to predetermined signals. Upon the selection of either bar, longitudinal motion is imparted thereto which through its pivotal connection with an operating lever is communicated to other means to effect the transverse shifting of the saddle member.

For a more comprehensive understanding of this invention, reference will be had to the accompanying drawing, taken in connection with the following description wherein like reference characters indicate similar parts throughout. In the drawing:

Fig. 1 is a front elevation of a linecasting machine assembling block and a portion of the automatic control unit in section with intervening parts broken away to simplify the disclosure;

Fig. 2 is a transverse section taken approximately on line 2—2 of Fig. 1;

Fig. 3 is a plan sectional view taken approximately on line 3—3 of Fig. 1, and

Fig. 4 is a detail perspective view of the saddle member referred to above.

In its preferred embodiment, the present invention is shown as applied to a shiftable rail 11 capable of assuming two positions within the assembling block 12. In its left-hand position, as illustrated in Fig. 1, a small clearance 13 is afforded near the ingress portion of the block 12 whereby incoming matrices being unsupported are permitted to descend to a lower level, as indicated by the foremost matrices 14 of Fig. 2. When in its alternative position, rail 11 is presented within the space 13 so that matrices received thereafter will be supported by the rail 40 and will assume a position as illustrated by the rearmost assembled matrices 15. Depending on which of these alternative positions each matrix is supported, it accordingly presents one or the other of two matrix impressions or intaglio carriers thereby to the level which registers opposite the casting mold when, in the course of subsequent operations, the assembled line of matrices is transported to the slug casting mechanism.

The two intaglios carried by each matrix are customarily of the same alphabetical or numerical character, but of a different font or type class. Among the more common classes of the two types of intaglios are the bold face which is presented by the matrices in the position indicated 15, and the Roman face which is presented by the matrices in the position indicated 14. Hence, for convenience in the course of the following description, the upper position of a received matrix and the corresponding relation of any of the shiftable associate mechanism will be referred to as the bold position, while the opposite condition of any of the aforesaid elements will be referred to as the Roman position.

The rail 11 is slidably supported within the slot 16 in the assembling block and is moved into each of its positions through the agency of a bell crank 17 pivoted at 18 and connected to the rail at 19 and to a connecting link 22 at 21. The opposite end of link 22 is pivotally jointed to one arm 23 of a bell crank 24 which is mounted on a stud shaft 25. Another arm 26 of bell crank 24 is slotted at its end as at 27 and is adapted thereto to engage a stub pin 28 which is secured to an upstanding member 29 of a saddle 31. The saddle 31, its stub pin 28, and its upstanding

member 29 form an integral assembly including, in addition, a pair of symmetrically and oppositely disposed lugs 32 which project inwardly, as best indicated in Figs. 2 and 4.

A constantly rotating shaft 33, extending sidewaysly through the frame 34 which in the accompanying drawing represents the supporting structure of the principal portion of the control unit, may be any continuously operated shaft such as, for example, the shaft 47 illustrated in the copending application referred to above. The end of shaft 33, as illustrated in the accompanying drawing, carries a bushing upon whose periphery is formed a pair of oppositely inclined threaded portions or helices 35 and 36. The transverse distance between the opposite lugs 32 is such that as one of them engages the threads of its associated helix 35 or 36, the other of them just clears the threads of its associated helix, as best indicated in Fig. 2. During the rotation of shaft 33, after one of the projections 32 is presented within the threads of its helix, the entire saddle 31 and its assembly are moved longitudinally thereby in a direction depending upon the inclination of the helix. This movement continues until the projection 32 is drawn beyond the extremity of the threads of its associate helix, at which time the opposite projection 32, when selected, engages the rearmost portions of its associate helix, which thereupon moves the assembly 31 in the opposite direction until its limit is reached.

The saddle 31 and its assembly are supported for longitudinal as well as slight transverse movement within a slot 37, Fig. 3, of a bracket 38 which is in turn supported for horizontal and parallel movement upon a shouldered pin 39, Fig. 1. An extremity 41 of bracket 38, having provided therein an elongated slot 42, Fig. 2, permits of the horizontal movement of bracket 38 when actuated by the oscillation of a lever 43.

The lever 43 is pivotally supported upon a boss 44 formed in the frame 34 and is bifurcated at its upper extremity as at 45. Between the tines of fork 45 there is presented the extremity 45 of a lever 46 pivotally mounted at points 47 and 48 upon each of a pair of selectable bars 49 and 51. The bars 49 and 51 comprise two of a plurality of similar bars such as the bars 35, illustrated in the above referred to copending application, and upon their selection are moved from a normal position, as illustrated by bar 49 in Fig. 3, to a selected position as illustrated by bar 51. Each of these bars 49 and 51 may be thus selectively moved in response to a received signal individual thereto. After any of the bars such as bars 49 and 51 are selectively operated it is then withdrawn by the periodic intervention of a transverse bail 50 which returns all of the bars after a predetermined interval in each operating cycle. When, as in the illustration Fig. 3, and in response to a Roman shift signal bar 51 is selectively moved forward, the point 47 of bar 49 becomes the fixed pivotal point about which lever 46 turns, acting thereby as a first-class lever and causing its extremity to engage the lower tine of the fork 45, moving lever 43 clockwise as viewed in Fig. 2, and causing the projection 32 which is associated with worm 36 to be presented thereinto. But when, on the other hand, a bold shift signal is received with bar 51 in its normal position, bar 49 is selectively moved forward, and point 48 of bar 51 becomes the pivot for lever 46 which then moves in an opposite direction acting as a third-class lever. In bold shift

operation, lever 46 engages the upper tine of fork 45, Fig. 3, moving lever 43 in a counterclockwise direction, as viewed in Fig. 2, and causing the movement of saddle 31 to be reversed so as to present its opposite lug 32 within the threads of worm section 35. The direction of longitudinal movement of saddle 31 depends, as explained above, upon which of the two lugs 32 engages its associated worm section 35 or 36. Following the selection of bar 51, as a result of which worm section 36 is engaged, saddle 31 moves to its right-hand extremity, as illustrated in Fig. 1, causing the rail 11 through the linkage 24, 22 and 17 to be presented in its Roman position; that is, where the space 13 is unoccupied so as to permit subsequently received matrices to descend to the level represented by the matrix 14. When bar 49 is selected, resulting in worm section 35 being engaged by its lug 32, saddle 31 advances in an opposite direction or to its left-hand position, where, through the same linkage 24, 22, and 17, rail 11 is presented in its bold position, occupying the space 13 and preventing subsequently received matrices from descending to the lower or Roman position, but being instead, continuously supported in the upper or bold position, as indicated by the matrices 15.

It will be noticed that the movement of saddle 31 under the actuation of worms 35 and 36 is considerably reduced in speed by the inherent characteristics of the worm actuators 35 and 36. Thus, the resultant movement of rail 11 is effectuated in a much slower or retarded movement as compared with the pace of the principal selecting functions represented by the speed of shaft 33. As a result of this retardation in the response of rail 11 to the bold and Roman shift signals for shifting it in one direction or the other, a certain time interval is permitted during which previously released matrices which are intended to be received with the rail 11 in a given position may have time to descend, settle, and be properly received, whereas, otherwise with the rail 11 responding naturally or at the prevailing pace to the selection of its bar 49 or 51, its movement would more than likely precede the reception of the last one or two matrices which are intended to be received in a previous condition thereof, causing them instead to be received in the changed position of rail 11. In the case of exceptionally wide matrices which precede rail shift signals it has been found advantageous to introduce blank signals before the rail shift signal to augment the prolongation of the rail shift operation so as to afford a delay even in the initial signal transfer and before the rail has had any opportunity to move. The presence of blank signals in the control form, as may be ascertained from the application referred to, results in a mere idle operation of the control unit mechanism, no matrices being released nor other functions executed during their occurrence, thereby allowing sufficient time for other functions to be performed.

An alternative arrangement for suspending the performance of the control unit is illustrated in the copending application. In accordance with that disclosure the record reader mechanism is arrested while the retarded operating mechanism is performing. A structure of this kind may be incorporated with the present invention if preferred in favor of providing additional blank perforation in the control form.

Though this invention has been explained and

described in connection with retarding the response of the bold and Roman rail shift operations, it should be understood that other special functions of a principal selecting machine may similarly be controlled and it should therefore be understood to have general application, though described in connection with a particular example.

Because numerous changes and modifications may be made without departing from the spirit or scope of the present invention, it is intended not to be limited to the specific language of the foregoing description nor to the details of the accompanying drawing, but to be permitted, instead, a latitude of construction as indicated by the hereunto appended claims.

What is claimed is:

1. In a line composing machine, the combination of a matrix assembling block, a rail shiftable into alternative positions for modifying the reception of selectively released matrices within said block, means for shifting said rail, and a retarded motion mechanism for deferring the response of said rail including a duplex driving mechanism for initiating motion in two directions at a reduced speed, means for actuating said mechanism at a derived speed, and a linkage movable in two directions by alternative portions of said mechanism for accordingly imparting selective responses to said rail at said reduced speed. 30

2. In a line composing machine, an assembling rail, means for moving said rail into two positions including a saddle member, a pair of helical actuators, means under the control of certain signals for moving said saddle member into engagement with one of said helical actuators, means under control of other signals for moving said saddle member into engagement with the other of said helical actuators, and means for impelling said actuators at a given speed for imparting motion through said helical actuators at a reduced speed. 40

3. In a line composing machine, a shiftable rail, a signal controlled mechanism responsive to each of a pair of signals for shifting said rail into corresponding alternative positions, and means for delaying the responsive movement of said rail to said mechanism including a pair of worm actuators, and means for associating said actuators selectively with said rail in accordance with 50 corresponding control signals.

4. In a line composing machine, a shiftable assembler rail, a mechanism responsive to signal control for shifting said rail into each of alternative positions including a pair of selectable bars, 55 a power take-off means, an operating train for said shifting mechanism communicating with said power take-off means including a pair of worm actuators driven by said power take-off means having oppositely inclined helices, a 60 mechanical train connecting said rail with said actuators, and means under the control of said selectable bars for associating said train with corresponding ones of said actuators under the control of predetermined signals. 65

5. In a line composing machine, a shiftable assembler rail, a pair of alternatively effective driving worms, a power take-off means for actuating said worms, a motion receiving element 70 capable of being brought into operative relation with each of said worms individually, and means for shifting said element including a supporting member, a lever for shifting said member, a pair of signal responsive selectable bars, and means 75

for pivotally securing said lever to each of said bars so that through the selective motion of each and the pivotal cooperation of the other said shiftable element is brought into engagement with the corresponding ones of said worms.

5. 6. In a mechanism for automatically controlling a series of selectable functions certain of which are to be executed at a given speed and certain others of which are to be executed at a reduced speed, the combination with the driving means having a given speed for performing certain of said functions, of means having a reduced speed for performing the other of said functions including a pair of oppositely inclined 10 worm actuators, a pair of selectable elements, a linkage associated with mechanism to be operated with retarded response, means under the control of one of said elements for associating said linkage with one of said worms, and means under the control of the other of said elements 15 for associating said linkage with the other of said worms.

7. A speed reduction mechanism including a driving source having a given speed, a pair of integrally mounted worms of opposite inclination, connections for transmitting motion from said source to said worms, an actuator for receiving retarded motion including an apparatus supported for two-directional movement, and means associated with said actuator for engaging each 20 of said worms individually.

8. In a machine of uniform speed operation, a retarded response mechanism including a pair of integral worm actuators, a driving connection between said actuators and the driving mechanism of the machine, an apparatus to be operated with a retarded motion, and means for receiving said 25

motion including a pair of followers and means for individually engaging each of said followers with associated ones of said worm actuators.

9. In a mechanism of automatic control, a plurality of elements individually selected for operation, means for moving conditioned ones of said elements in a common direction, and means for effecting a two-directional control through the selective movement of two of said elements in the same direction comprising an actuator pivoted to the two of said elements so that upon the selective movement of either the other may function as the fixed pivot.

10. In an automatic selecting device, including a plurality of elements selectively movable in one direction, means for effecting a two-directional control comprising a lever pivoted transversely to two of said elements so that the selective movement of either and the inert condition of the other accordingly governs the direction 15 of rotation of said lever.

11. In a linecasting and composing machine, a plurality of selectable elements to be individually conditioned for initiating various casting and composing functions, a power driven mechanism 20 having continuous motion in one direction, and means under the control of certain of said selectable elements for communicating motion from said power driven mechanism alternatively in two directions comprising a member having inwardly 25 extending projections adapted to be brought into engagement alternatively with said power driven mechanism by being shifted transversely thereof and to communicate the motion received from said mechanism longitudinally thereof.
